UNITED STATES PATENT OFFICE.

GEORGE W. COY, OF MILFORD, CONNECTICUT, ASSIGNOR, BY MESNE ASSIGNMENTS, TO THE UNITED STATES TELEPHONE MANUFACTURING COMPANY, OF NEW YORK, N. Y.

TELEPHONE-EXCHANGE SYSTEM.

SPECIFICATION forming part of Letters Patent No. 257,664, dated May 9, 1882.

Application filed December 31, 1880. (No model.)

To all whom it may concern:

Be it known that I, GEO. W. COY, a citizen of the United States, residing at Milford, in the county of New Haven and State of Connecticut, have invented certain new and useful Improvements in Telephone-Exchange Systems; and I do hereby declare the following to be a full, clear, and exact description of the invention, such as will enable others skilled in the art to which it appertains to make and use the same, reference being had to the accompanying drawing, and to letters or figures of reference marked thereon, which forms a part of this specification.

15 My invention relates to telephone-exchange apparatus, the object being to facilitate the operation of placing subscribers in communication. To this end my invention consists in certain combinations of apparatus, which will 20 be particularly described, and then pointed out in the claims.

In the accompanying drawing I have shown my invention applied to a system in which a listening-telephone normally connected to the 25 several lines is used at the central office, and resistances are placed at the subscribers' stations to prevent the diversion of the telephonic currents coming from a subscriber's station to the central-office telephone. I do not, however, 30 claim the arrangement of the resistances or the particular arrangement of the receiving-telephone with relation to the lines as my invention, and I wish it to be understood that the particular invention herein claimed may 35 be used in conjunction with other arrangement of those devices besides those shown.

The drawing is a diagram of the central-office apparatus and the devices used at the various subscribers' stations. But two stations 40 are represented for the sake of simplicity.

A represents a portion of the central-office switch-board, consisting of vertical strips 1 2 3, each connected to an independent line-wire, and suitably perforated for the reception of the 45 switch-pins, and horizontal strips *a b c*, either of which may be used in the well-known way as a connector between the vertical strips. The strips 1 2 3 are at their lower ends suitably cut away for the reception of switch-plugs, 50 which connect all the lines to a common plate,

B, connected through a listening-telephone, L T, with the ground. Drop-annunciators, one in each line-circuit, are shown at W. The lines 1 2 3 are connected to the annunciators through circuit-shifting apparatus K. Said 55 boards may be operated so as to connect any line-wire to a branch wire leading to a generator of electricity common to said lines, (represented at M B as a battery,) when it is desired to signal from the central office to a subscriber.

The apparatus at the subscriber's station consists of an ordinary two-point switch, S' S², one of whose studs connects through wire 9, 60 secondary of the induction-coil in transmitter M, and wire 10 with the ground E. The other stud connects through call-bell H with a carbon resistance, C, or other form of resistance free from self-induction, and with the ground.

A circuit-shifting apparatus, K, serves to 70 break the connection of the line 1 with the switch S' and make a connection through wire 13 with one pole of the local transmitter-battery L, the other pole of which has an earth connection. When this is done the current 75 from the battery circulates over the line and through the drop-annunciator, thus causing the drop of the annunciator to fall to indicate the line from which the signal comes.

The battery L is connected, as usual, with 80 contact-points of the transmitter and the primary of the induction-coil, and by this arrangement is made to serve both the purpose of a local battery for the transmitter and a signaling-battery for signaling to the central 85 office.

Each subscriber's station is to be provided with devices substantially the same as those just described as connected with line 1.

The circuit from each subscriber's station to 90 the central office and annunciator is normally through the subscriber's bell or main line and switch K to the line-strip of the switch-board, and to ground through the telephone at the central office.

At the subscriber's station the line is normally connected to the earth through the circuit-shifting apparatus K, switch-lever S', call-bell H, and resistance C.

By turning the switch-lever S', so as to con- 100

nect the line to earth through his telephone, the subscriber may inform the listening operator of the connection desired.

The resistances C in the several lines serve 5 to prevent the diversion of the telephonic currents which would otherwise take place through the bar B and the strips connected to the same and to the lines.

The switch-board operator, having been notified of the number of the wire or of the subscriber with which the calling subscriber is to be connected, immediately operates the circuit-shifting apparatus in the line of the subscriber asked for, so as to connect said line to the wire 15 leading to the electric generator, and rings the bell at that subscriber's station. He then shifts the plugs at the bottom of the line-strips to any one of the horizontal connecting-strips not in use, which act disconnects the lines from 20 the telephone L T, and connects them when the annunciators are located on the normal line-circuits at the point here shown through said annunciators. The operation of the circuit-shifter K will in the above arrangement 25 disconnect the line from the circuit leading to the annunciator and normal ground, thereby preventing the current of the generator M B from passing to earth at the central office or from affecting the annunciator-card. When 30 the subscribers have finished their communication the circuit-shifting apparatus at either station may be operated so as to throw battery L to line, upon which the annunciator-drops in the connected lines are made to fall, giving notice 35 at the central office that the lines are to be disconnected.

Instead of the apparatus used on line 1 for connecting the local battery to line, when it is desired to operate the annunciator in the direct 40 line circuit at the central office, I may employ other devices—as, for instance, apparatus such as that shown on line 2, where M E represent a magneto-electric machine or generator of any preferred construction, to the box 45 of which is attached an electro-magnetic call-bell for receiving the signal from the central office. A push-button, which serves to throw the coils of the machine into circuit, and, if desired, to simultaneously throw out the bell, 50 is indicated at p.

Other forms of switches and connecting apparatus may be used at the central office and at the subscribers' stations in place of those shown. The forms indicated have been adopted 55 in describing the invention for the sake of simplicity. Many others may be adopted or devised for producing the changes in the circuits which have been described.

Any ordinary form of switch may be used in 60 the local circuit for breaking the circuit of the battery L when the transmitter is not in use.

The particular location of the annunciator directly in each line-circuit at a point where when two lines are connected the annunciators will be in circuit between them forms no part of the invention herein claimed. It is obvious that the annunciators might be placed

in other locations as well as in that described with relation to the connecting apparatus, circuit-shifters, lines, &c., without departing from the spirit of the invention. I do not herein 70 make any claim to the combination of a central-office telephone-switch and a disconnecting annunciator interposed between two connected lines for the purpose of notifying the 75 central-office operator to disconnect the line upon the discontinuance of conversation, as this forms the subject of a division of the present application; nor does "the combination at a central office of a line connecting two subscribers with a signaling device located in said line, whereby the operator may be notified to disconnect the subscribers' lines upon the discontinuance of conversation," form any portion of the present invention. 80 85

The particular arrangement herein shown of a disconnecting annunciator with relation to the switch-board and the circuit-shifters, whereby the operation of signaling to a line after the two lines are connected does not affect the annunciator, is reserved for the subject of another application. 90

I do not claim the employment of carbon resistances in the manner set forth in this specification for the purpose of preventing the diversion from a common listening-telephone of the telephonic currents coming from a subscriber's station. 95

What I claim as my invention is—

1. The combination, substantially as described, of a series of telephone-lines centering in a single office, switch apparatus for connecting any two of said lines for telephonic communication, an annunciator in each normal line-circuit and in direct connection with said circuit, and circuit-shifting apparatus for connecting any line at pleasure to a wire leading to an electric generator for signaling to a subscriber's station. 100 105

2. The combination, substantially as described, of a series of telephone-lines, a common switch apparatus for connecting any two lines for telephonic communication, an annunciator at the central office placed directly in each normal line-circuit, an electric generator in a 115 branch line for signaling purposes, and circuit-shifting apparatus for disconnecting any line from the portion of its normal circuit running to the annunciator and ground and connecting said line to the wire leading to the generator. 120 125

3. In a station telephone apparatus, a battery in a local circuit, in combination with a switch in the line having connections to the station apparatus and the local battery, and acting to disconnect the line from the station apparatus and connect it with the local battery, substantially as and for the purpose described.

In testimony whereof I affix my signature 130 in presence of two witnesses.

Witnesses: GEORGE W. COY.
